Primary Examiner — Kevin K Rudzinski*(74) Attorney, Agent, or Firm* — Frost Brown Todd LLC**(57) CLAIM**

The ornamental design for a braking unit column, as shown and described.

DESCRIPTION

FIG. 1 is a top right perspective view of a braking unit column showing our new design;

FIG. 2 is a bottom right perspective view thereof;

FIG. 3 is a front elevational view of thereof;

FIG. 4 is a rear elevational view thereof;

FIG. 5 is a left elevational view thereof;

FIG. 6 is a right elevational view thereof;

FIG. 7 is a top plan view thereof; and,

FIG. 8 is a bottom plan view thereof.

The evenly spaced broken lines in the drawings depict portions of the braking unit column that form no part of the claimed design.

1 Claim, 8 Drawing Sheets(56)
